UNITED STATES PATENT OFFICE

HERMAN ALLBOOK AND MORRIS HASHFIELD, OF LONDON, ENGLAND

FUR-OVERSEAMING MACHINE

Application filed March 15, 1928, Serial No. 261,888, and in Great Britain March 16, 1927.

This invention has reference to improvements in or relating to fur-overseaming machines, and the main object of our invention is the provision of improved supporting and positioning means for the looper carrier whereby not only the correct adjustment and alignment of the looper is facilitated but also whereby desirable alteration in its lift is made easily attainable and withal vibration is reduced to a practical minimum.

10 In the accompanying drawings:

Figure 1 is a longitudinal section of the machine, the parts being in elevation;

Fig. 2 is a plan;

15 Fig. 3 is a cross-section, and

Figs. 4, 5 and 6 show the two adjustable pins, studs or bolts below the rear end of the looper carrier, in three relative perpendicular views.

20 According to our invention the looper carrier 1 is supported at its rear end by an adjustable bearing 2 whereby speedy and precise adjustment of the looper 3 may be effected; and at or near its front end by a pair of trunnions 4 the axes of which are coincident and pass through the longitudinal axis of the looper carrier 1 or the looper bar 5 carried thereby, the trunnion pins 4 being supported on a pair of links 7 by adjustment of which 25 the position of the carrier 1 in the direction transverse to the vertical plane in which the needle 8 operates may be effected and by which any slack brought about by wear may readily be taken up.

30 The front supports 9 and rear support 2 are as far apart as the dimensions of the usual casing admits of whereby the looper carrier 1 is more firmly supported and less liable to vibrate than is the case when, as heretofore, the said supports are fairly close together.

In some of the heavier classes of work it is necessary or desirable that the looper should dip lower behind the needle than is desirable for lighter work and in order that this may 35 readily be effected one of the supports 9 or 2, preferably the rear, 2, is adjustable in relation to the other whereby the amount or extent of lift of the looper 3 may be regulated. It is also desirable that the lowest position to 40 which the looper extends during the opera-

tion of the machine should be capable of adjustment without altering the amount or extent of lift of the looper and this we attain by tilting the looper carrier 1 about the trunnions 4 referred to.

45 Further, the trunnions 4, being provided on opposite sides of the carrier 1 described, will ensure a more firm support thereto and will also avoid undue wear of the bearing which takes place when but a single trunnion 50 is provided, and also will assist in reducing vibration.

In accordance with a preferred constructional form of our invention, we provide at the rear end of the machine casing a stationary vertically disposed bearing 10 adapted to receive slidably thereon a stud 11 on the upper end of which is a clamp 12. Adjustably secured in said clamp is a pin or stud 13, disposed longitudinally of the machine, and having at its front end bearing 2 in which a spindle 14 is carried.

60 Said spindle 14 carries, at one end, a depending link 15 capable of swinging movement, the spindle being held fast in the link 65 by a set screw. A collar 16 is provided on the spindle 14 at the end opposite to that on which the link 15 is mounted. This collar may be adjusted to take up wear of the bearing 2 and is secured in adjusted position by 70 means of the set screw 17.

75 Secured to the lower end of the link 15 by means of a set screw 18, is a pin 19 that enters an aperture in the rear end of the looper carrier 1, and whereby the rear end of said carrier is supported. Said pin 19 has a shoulder 20 which keeps the end of the looper carrier 1 rigid laterally with the link 15.

80 The looper carrier 1, near its front end, is provided with two oppositely disposed tubular extensions 6 or sleeve-like members the axes of which are coincident and pass through the longitudinal axis of the looper carrier 1 or the looper bar 5 carried thereby. Into 85 each of the said members 6 a trunnion pin 4 is entered, the trunnion pins being supported on links 7 (and secured thereto by set screws 21) that are secured (also by set screws 22) to a shaft 23 so that the links 7 are adapted for 90 swinging movements. Said shaft 23 is car- 95

100

ried in bearings 9 in the machine casing and may be maintained in position transversely of the machine by means of two collars thereon, one engaging the casing inside and the other outside. Or said shaft 23 may be provided at one end with a head 24 to engage the outside of the casing, and at the other end with a nut or collar 25 which also engages said casing. One of the links 7 is provided with an extension 26 which is pivoted to one end of a member 27 the other end of which is connected to or is formed integral with the strap 28 of an eccentric 29 whereby said link 7, 26, is rocked thereby, imparting oscillations to the looper carrier 1 longitudinally of the machine and at the same time imparting the required lift thereto.

The swinging links 7 maintain the position of the looper carrier 1 transversely of the machine and by adjusting them to one side or the other the looper carrier will receive corresponding transverse adjustment. Adjustment of said links 7 will also serve to take up any slack caused by wear.

25 The front and rear supports of the looper carrier, that is to say the trunnion pins 4 in front and the spindle 14 at the rear, are as already stated, as far apart as the dimensions of the usual casing admits of.

30 In order to vary the amount or extent of lift imparted to the looper 3 all that is necessary is to loosen the clamp 12 (by screw 30) referred to and to adjust the stud 13 carried therein (and consequently the bearing 2, spindle 14, and upper end of the link 15 mounted on said spindle) forwardly or backwardly. This will cause the link 15, during the operation of the machine, to swing through a greater or less angle according to the adjustment made.

35 In order to vary the lowest position to which the looper reaches without altering the amount of its lift, the stud 11 in the vertically disposed bearing 10 will be adjusted, a set screw 31 being provided to secure the stud in adjusted position. In order that a very fine and precise adjustment may be obtained, we provide the stud 11 or clamp 12 with two lugs 32 the upper and lower faces of which 40 are respectively engaged by collars formed integrally with a second stud 33 that is screwed into the machine casing so that by screwing it up or down the clamp will be correspondingly adjusted. The upper end 34 of said collars 45 may be suitably formed to be engaged by a screw driver or spanner.

The looper bar 5 is provided with an adjustable collar 35 and a set screw. Said bar is entered into the tubular looper carrier until said collar abuts against the front end of the carrier, and is secured in position by a collar 36 and set screw on its rear end, which collar abuts against a shoulder on the carrier.

60 65 The collar on the rear end of the bar is pref-

erably provided with an extension on which is a cam roll that enters a cam groove 37 whereby the looper bar 5 is caused to oscillate about its axis.

The usual feed cups and needle are provided, together with cams or other devices for actuating all the mechanisms in timed relation.

70 Although the above described preferred constructional form of our invention forms an important feature thereof, we wish it to be understood that we do not limit the scope of our invention thereto.

75 What we claim as new, is:

1. In an overseaming machine for fur and gloves, the combination of a main frame, a power shaft thereon, a horizontally movable needle, a looper above the needle and having forward and backward, up and down, and sidewise movements, a looper carrier, means for supporting the forward end of the looper carrier comprising a pair of links, supported from the frame and which are mutually adjustable for supporting the looper carrier between them, and operably connected with the power shaft for receiving a swinging motion, and means for supporting the rear end of the looper carrier comprising a longitudinally adjustable pin or stud supported from the frame so as to be parallel with the needle and having a bearing, and a link journaled in and depending from the bearing, and connected with the looper carrier.

80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

2. In an overseaming machine for fur and gloves, the combination of a main frame, a power shaft thereon, a horizontally movable needle, a looper above the needle and having forward and backward, up and down, and sidewise movements, a looper carrier, means for supporting the forward end of the looper carrier comprising a pair of links, supported from the frame and which are mutually adjustable for supporting the looper carrier between them, and operably connected with the power shaft for receiving a swinging motion, and means for supporting the rear end of the looper carrier comprising a pin mounted on the frame in vertically adjustable position, a clamp on the pin, a horizontal pin or stud secured adjustably in the clamp and extending parallel with the needle and having a bearing, and a link journaled in and depending from the bearing and connected with the looper carrier.

3. In an overseaming machine for fur and gloves, the combination of a main frame, a power shaft thereon, a horizontally movable needle, a looper above the needle and having forward and backward, up and down, and sidewise movements, a looper carrier, means for supporting the forward end of the looper carrier comprising a pair of links, supported from the frame and which are mutually adjustable for supporting the looper carrier between them, and operably connected with

the power shaft for receiving a swing motion, and means for supporting the rear end of the looper carrier comprising a pin vertically slidable in the frame of the machine and supporting a clamp, a horizontal pin or stud secured to the clamp and extending parallel with the needle and having a bearing, a link journaled in and depending from the bearing and connected with the looper carrier, and a screw parallel with and connected with the vertical pin and screwed into the frame for a vertical adjustment, whereby to alter the height of the looper.
